PRODUCTION OF ESTERS

Heinrich Bertsch, Chemnitz, Germany, assignor
to H. Th. Böhme Aktiengesellschaft, Chem-
nitz, Germany, a corporation of Germany

No Drawing. Application January 29, 1930, Serial
No. 424,456. In Germany February 6, 1929

15 Claims. (Cl. 260—99.12)

In my prior Patent 1,823,815, granted September 15, 1931 is described a process for the production of esters of the sulpho-acids which may be formed by the sulphonation of glyceride fats, cholesteride fats and the corresponding fatty acids and also of esters of the aromatic sulpho-acids which are at the same time cyclic carboxylic acids or carboxylic acids in the side chain. Said process consists in first producing the esters of the carboxylic acids with alcohol radicals having a low carbon number (say up to cetyl alcohol) and then sulphonating said esters. The result of this process was that in the sulphonating step not only did sulphonation of the esters take place but also the alkyl or aryl radical attached to the carboxyl group passed wholly or in part to the sulphuric acid radical group so that the end product consisted of esters of the sulpho-fatty acids, possibly in admixture with carboxylic acid esters or with esters in which both the sulphuric acid radical and carboxyl group were esterified.

One object of this invention is to provide alternative means for arriving at the results described. According to one feature of this invention the above reaction can be performed even more smoothly if an intensive sulphonating and sulphating agent is caused to act upon the lower carboxylic acid esters. Such an agent may be a sulphonating agent the effects of which have been improved by appropriate additions or may be a sulphonating agent which by itself acts very energetically. Furthermore such improving additions may also be made to sulphonating agents which are already energetic by themselves. The temperature is preferably kept below 15° C. whereby saponification of the esters to be sulphonated is avoided or confined to a very small amount and the yield is correspondingly improved. As energetic sulphonating agents use may for instance be made of fuming sulphuric acid, sulphur trioxide (preferably in vapour form or as high percentage oleum) or chloro-sulphonic acid. Mixtures of concentrated sulphuric acid, or of the sulphonating agents just mentioned, with anhydrous lower fatty acids, their anhydrides or chlorides, for example mixtures of fuming sulphuric acid with acetic anhydride may also be employed. Alternatively the sulphonating agents may be allowed to react with the lower fatty acids or their derivatives and the resultant products, for instance acetyl sulphuric acid, caused to act, either alone or in mixture with sulphuric acid or the like, upon the carboxylic acid esters. Finally also, alkyl derivatives of sulphuric acid or chloro-sulphonic acid may

be used alone or in admixture with other sulphonating agents. By such means products are obtained which, for the greatest part, are esterified both in the sulpho-group and in the carboxyl group.

Example 1

75 kgs. of oleum having a 30% sulphur trioxide content are gradually added over a period of several hours to 100 kgs. of ricinoleic acid -n-butyl ester, maintained at a temperature below 5° C. during which time the mass is vigorously stirred. The stirring is continued for an hour or so after the addition has been completed. To the crude sulphonation product there is added an equal amount by weight of crushed ice. The mass is stirred thoroughly, allowed to settle until a film forms and the collected dilute acid poured off. The oily product is then agitated with Glauber's salt solution and again allowed to settle whereupon the salt solution is separated. The oil can then be neutralized with soda liquor if so desired. So far as is known, the structure of the product may be represented by the following formula:

Example 2

In a similar manner 100 kgs. of ricinoleic acid methyl cyclohexanol ester are sulphonated, at a temperature below 0° C. and in the presence of 100 kgs. of ethyl ether, with 30 kgs. of chloro-sulphonic acid. Ice is added to the reaction product which is washed with Glauber's salt solution. Finally the ether is distilled off in vacuo. So far as is known, the structure of the product may be represented by the following formula:

Example 3

100 kgs. of oleic acid benzyl ester are sulphonated with 100 kgs. of oleum (10% SO₃). The preparation is continued as in Example 1. So far as is known, the structure of the product may be represented by the following formula:

Example 4

100 kgs. of ricinoleic acid-iso-butyl ester are sulphonated with 100 kgs. of oleum (10% SO₃) in the presence of 100 kgs. of acetic anhydride. The preparation is continued as in Example 1.

So far as is known, the structure of the product may be represented by the following formula:

Example 5

100 kgs. of naphthoic acid-iso-propyl ester are sulphonated with 60 kgs. of chloro-sulphonic acid. The preparation is continued as in Example 1.

The esters produced in the manner described exhibit to an enhanced extent the valuable properties of the products described in my prior Patent 1,823,815 hereinbefore referred to and may therefore be similarly used with advantage in the most diverse branches of industry as wetting, penetrating, foaming, dispersion and like agents. So far as is known, the structure of the product may be represented by the following formula:

According to a further feature of this invention said esters may also be obtained in good yields direct from the carboxylic acids, without concomitant reactions causing disturbance to any material extent, if the intensive or energetic sulphonating agents are caused to act upon the carboxylic acids themselves and the alcohol, with which a carboxylic acid or sulpho acid, is to be esterified, is added to one of the reaction components or to the reaction mixture before, during or after the sulphonation. As already pointed out these intensive or energetic sulphonating agents are substances such as fuming sulphuric acid, sulphur trioxide (preferably in vapour form or as high percentage oleum) and chloro-sulphonic acid or mixtures of concentrated sulphuric acid, or of the sulphonating agents just referred to, with anhydrous lower fatty acids, their anhydrides or chlorides.

The process may for example, be carried into effect by treating an appropriate carboxylic acid of high molecular weight with one of the sulphonating agents or mixtures referred to and adding the appropriate alcohol to the raw sulphonation product. Alternatively the alcohol may be mixed with the carboxylic acid and the sulphonating agent then caused to act upon the mixture. Alternatively again it is possible to work direct with the appropriate alkyl sulphuric acid or alkyl sulpho-chloride. Preferably a temperature below 15° C. is adhered to during the sulphonation.

It will be observed that this application deals chiefly with the treatment of unsaturated and hydroxy fatty acids and their esters, but unsaturated acids as described herein are to be understood as including those which contain aromatic nuclei.

Example 6.

100 kgs. of ricinoleic fatty acid are sulphonated with 90 kgs. of oleum (30% SO₃) at a temperature below 5° C. 25 kgs. of iso-butyl alcohol are added to the raw sulphonation product during stirring which is continued for several hours. After the reaction has ended, ice is added and the reaction product is washed with Glauber's

salt solution. The structural formula is similar to that of Example 1.

Example 7

100 kgs. of 12-hydroxy-stearic acid are mixed with 50 kgs. of butyl alcohol and sulphonated at a temperature below 0° C. with 36 kgs. of chloro-sulphonic acid. After the reaction has ended, the preparation is continued as in Example 6. So far as is known, the structure of the product may be represented by the following formula:

Example 8

100 kgs. of oleic acid are sulphonated at a temperature below 5° C. with 30 kgs. of acetic anhydride and 100 kgs. of oleum (10% SO₃). 45 kgs. of iso-propyl alcohol are added to the crude sulphonation product. The preparation is continued as in Example 6. So far as is known, the structure of the product may be represented by the following formula:

In place of acetic anhydride, an equivalent amount of acetyl sulphuric acid may be used and the quantity of oleum added may, if desired, be reduced accordingly.

Example 9

100 kgs. of naphthoic acid are sulphonated with 70 kgs. of chloro-sulphonic acid. 35 kgs. of iso-propyl alcohol are added to the crude sulphonation product. The preparation is continued as in Example 6. The structural formula is similar to that of Example 5.

Example 10

48 kgs. of butyl sulphuric acid are added to 100 kgs. of ricinoleic fatty acid at a temperature below 15° C. The preparation is continued as in Example 1.

Butyl sulphuric acid may be replaced by the equivalent amount of butyl sulphuric acid chloride.

While the term "sulphonation" is used throughout the specification and claims to describe the principal reaction, it is recognized in the art to which this invention relates that reactions of this character may result either in the formation of true sulphonic acids or sulphuric acid esters, or both, depending upon the conditions and the materials which enter into the reaction. For instance, in carrying out the process in the manner set forth in Examples 2, 7, and 10, sulphuric acid esters or sulphates are principally formed; in the reaction conducted in accordance with Examples 1, 3-6, and 8, mixtures of fatty sulphuric acid esters with fatty sulpho acids are formed; while in Example 9 aromatic sulpho acids are produced. It is therefore understood that the terms "sulphonation" and "sulphonation product" are used generically and are intended to cover the reaction and the reaction product resulting from the use of any well known sulphonating and sulphonating agent.

The principal reactions of the processes outlined in this application are believed to be properly represented by the following equations.

(I) Starting material: Unsaturated fatty acid + alcohol.

13. The process set forth in claim 10 in which the ester is derived from ricinoleic acid.

14. In the process of sulphating and sulphonating completely formed alkyl esters of unsaturated and hydroxy carboxylic acids having not less than 10 carbon atoms by the reaction therewith of a sulphonating agent, the step which comprises introducing in the reaction mixture a

sulphonation promotion medium comprising an anhydrous lower fatty acid radical compound, at a temperature below 15° C.

15. The process of forming esters of sulpho acids which comprises reacting a butyl ester of ricinoleic acid with an energetically acting sulphonating and sulphating medium. 5

HEINRICH BERTSCH.
